PROCESS OF OBTAINING COMMERCIAL GASOLINE FROM NATURAL-GAS GASOLINE.

Application filed September 26, 1923. Serial No. 665,018.

To all whom it may concern:

Be it known that we, HERMAN JAN MACKENZIE and ALEXANDER WILHELMUS STEENBERGH, both residing at Tjepoe, Java, 5 5 Dutch East Indies, have invented certain new and useful Improvements in Processes of Obtaining Commercial Gasoline from Natural-Gas Gasoline, of which the following is a specification.

10 Our invention relates to a process for obtaining commercial-gasoline from natural-gas gasoline.

Natural gas gasoline is a gasoline which is obtained from natural gas by means of 15 compression and condensation. In making this product a high pressure, for instance 16 k. g. per c. m.² is applied, so that the resulting liquid product contains a large quantity of hydrocarbons which will escape from 20 the liquid under normal conditions of pressure and temperature.

Upon releasing the pressure, evaporation arises, whereby primarily the permanent gases escape from the liquid. Moreover, in 25 applying this so-called weathering-process part of the liquid hydrocarbons will also evaporate, and this is undesirable, as these hydrocarbons are liquid under normal conditions and should remain in the commercial 30 gasoline. Further, the separation of these evaporable hydrocarbons from the permanent gases, is difficult and imperfect.

After this weathering the gasoline so treated is mixed with heavier varieties of 35 gasoline according to circumstances, in order to obtain a required market product.

The above-mentioned method has been improved, by adding the natural gas gasoline under pressure to the heavy gasoline 40 (the so-called blending gasoline) and by applying the weathering-process only thereafter. As a matter of fact, a decrease in the evaporation-losses is obtained, which must be ascribed to the fact that this heavy 45 gasoline keeps a greater quantity of the light hydrocarbons in solution. However, this method also has the above mentioned drawback, that, together, with the permanent gases, normally liquid hydrocarbons 50 also escape, which same, of course, it is desirable to retain in the gasoline.

Our invention practically removes this drawback, and embodies the characteristic that the so-called weathering-process is ex-

ecuted in applying a lower temperature. A 55 consequence thereof is that less of the valuable hydrocarbons escape with the permanent gases. The best results are obtained, if according to our invention, the temperature, or the temperature and pressure, is 60 gradually altered until the desired conditions of pressure and temperature are obtained. In this way a quiet and gradual gas development is obtained in releasing the pressure, so that the loss in valuable normally liquid hydrocarbons is reduced to a 65 minimum.

For illustrating the results obtained by the application of this invention, the following experiments are described.

1. In a container, 196.3 c. m.³ of blending gasoline were mixed under a compression-pressure of 17 atms. abs. with 177.7 c. m.³ of natural gas gasoline (obtained in the usual manner without taking any special 75 measures), and at a temperature of about 30° C. After releasing the pressure, 309.6 c. m.³ of normal gasoline remained. Assuming that none of the blending gasoline is lost then 309.6 c. m.³ — 196.3 c. m.³ — 80 113.3 c. m.³, or about 63.7 percent by volume of the original quantity of the natural gas gasoline remains.

2. The same container was filled with 200 c. m.³ of blending gasoline and mixed under 85 the same compression-pressure with 172 c. m.³ of natural gas gasoline (obtained in the usual manner without taking any special measure). This mixture was cooled down to —20° C., then the pressure was released 90 and the temperature was raised to that of the surrounding atmosphere. There results, 322 c. m.³ of mixture of about the same characteristics as obtained according to experiment 1. In this case 322 c. m.³ — 95 200 c. m.³ = 122 c. m.³ or about 70.9 percent by volume of the original quantity of the natural gas gasoline remains. This result, expressed in figures, shows that the application of this invention gives an advantage of 7.2 percent by volume over the known process.

For carrying out this process, apparatus is preferably used such as is indicated in the accompanying schematic drawings, 105 wherein the single figure shows a view of the entire plant.

The natural gas gasoline is supplied by

a compression-plant (not shown in the drawings), is freed from water as far as possible, and is then led through pipe 1 to a cooler 2. A cooler according to Liebig is used which is cooled by water. Through a pipe 3 the blending gasoline is supplied by a pump 21 from containers 19 and 20 via regulating valve 9 and is mixed at 4 with natural gas gasoline. The mixture thus obtained is run through salt-filters 5, which prevents icing in the cooling-system. From the salt-filters the mixture is run to a water and gas separator 6, and then through the inner pipe of a second cooler 7 and through a balanced container 8. This container is in connection with the valve 9, which regulates the supply of the blending gasoline.

From the container 8 the mixture still under pressure, runs through the inner pipes of some six coolers 10, of which the last is cooled by the aid of a solution from a refrigerator 11. After passing through the last cooler, the mixture runs through a main regulating valve 12 and into a gas-separator 13, in which with the aid of the valve 14, a pressure of, if possible, no more than one atmosphere is maintained.

In releasing the pressure at a low temperature, those parts are removed, which ought not to be present in commercial gasoline under normal conditions.

The cooling down of the mixture, arising from the removal of gases by evaporation, increases the effective output of the cooling-system. After leaving the separator 13 the gasoline mixture runs through the outer casings or jackets of the various coolers 10, as a result of which the temperature of the mixture gradually increases and through the various separators 13^a—13^e. The gases arising from the passage through the coolers, are separated out in the gas-separators 13^a, 13^b, 13^c, 13^d, and 13^e. By means of a centrifugal pump 15, beyond which is a regulating cock 16, the resulting gasoline is pumped from the last separator 13^e, through the casing of cooler 7, to gasoline storage tanks 17 and 18.

The pump 21 for the blending gasoline maintains a constant pressure in the pipe in front of the valve 9, which is some atmospheres higher than the pressure of the natural gas gasoline and which can be regulated by the valve 9.

The cooler 7 causes a re-cooling, and at the same time prevents gas from forming in the container 8, which might not otherwise operate properly.

This system has in view, to utilize, as far as possible, the cooling effect due to the evaporation of the fractions which are not desired in the commercial gasoline. However, in consequence of the larger quantity of conducted liquid, and the relatively large outer

surfaces of the cooling system, a second cooling is not necessary. The better the insulation of the system, and the exchange of heat in the system, the smaller can be the capacity of the cooling-plant.

We claim:

1. A process for obtaining commercial gasoline from gasoline-containing gas, comprising, compressing such gas, cooling the compressed gas to normal temperature while maintaining the compression pressure and separating out the resulting natural gas gasoline under pressure, then mixing the natural gas gasoline with blending gasoline, cooling the mixture to a relatively low temperature while maintaining it compressed, then releasing the pressure on the mixture to atmospheric pressure, then separating out the resulting gas from the liquid, the mixture being gradually brought to atmospheric temperature after the pressure has reached atmospheric, the separating out of the gas from the liquid being progressive and occurring over the entire period during which the mixture is coming to atmospheric temperature.

2. A process for obtaining commercial gasoline from gasoline-containing gas, comprising, compressing such gas, cooling the compressed gas to normal temperature while maintaining the compression pressure and separating out the resulting natural gas gasoline under pressure, then mixing the natural gas gasoline with blending gasoline, cooling the mixture to a relatively low temperature while maintaining it compressed, then releasing the pressure on the mixture to atmospheric pressure, then separating out the resulting gas from the liquid, said mixture being gradually brought to atmospheric temperature after the pressure has reached atmospheric, said separating out of the gas from the liquid being progressive and occurring over the entire period during which the mixture is coming to atmospheric temperature, said relatively low temperature being about -20° C.

3. A process for obtaining commercial gasoline from gasoline-containing gas, comprising, compressing such gas to about 17 atmospheres, separating out the resulting natural gas gasoline, at normal temperature and compression pressure, mixing the natural gas gasoline with blending gasoline, progressively cooling the mixture to about -20° C., then suddenly releasing the pressure on the mixture to about atmospheric pressure, and gradually bringing the temperature of the mixture back to normal while progressively separating out the gaseous element from the liquid portion.

In testimony whereof we affix our signatures.

HERMAN JAN MACKENZIE.

ALEXANDER WILHELMUS STEENBERGH.
